CLAIM

The ornamental design for a shoe outsole, as shown and described.

DESCRIPTION

FIG. 1 is a bottom view of a shoe outsole showing my design;

FIG. 2 is a rear side perspective view thereof;

FIG. 3 is a side perspective view thereof; and,

FIG. 4 is a front perspective view thereof.

The long-and-short broken lines form an unclaimed boundary around the claimed subject matter, and form no part of the claimed design. The even-length broken lines show the remainder of the article, are directed to environment, represent unclaimed subject matter, and form no part of the claimed design.
